DESIGN FOR A PHARMACEUTICAL PRODUCT SELECTOR AND DOSAGE CALCULATOR

James L. McDowell, Jr., Indianapolis, Ind., assignor to Eli Lilly and Company, Indianapolis, Ind., a corporation of Indiana

Application April 12, 1941, Serial No. 100,358

Term of patent 14 years

To all whom it may concern:

Be it known that I, James L. McDowell, Jr., a citizen of the United States, residing at Indianapolis, in the county of Marion and State of Indiana, have invented a new, original, and ornamental Design for a Pharmaceutical Product Selector and Dosage Calculator, of which the following is a specification, reference being had to the accompanying drawing, forming part thereof.

Fig. 1 is a front perspective view of a pharmaceutical product selector and dosage calculator showing my new design.

Fig. 2 is a rear perspective view of the pharmaceutical product selector and dosage calculator shown in Fig. 1.

Fig. 3 is a side elevation of the pharmaceutical product selector and dosage calculator shown in Figs. 1 and 2.

I claim:

The ornamental design for a pharmaceutical product selector and dosage calculator, as shown.
